UNITED STATES PATENT OFFICE.

WESLEY E. RAHR, OF BROOKLINE, MASSACHUSETTS, ASSIGNOR TO THE FLINTKOTE COMPANY, OF BOSTON, MASSACHUSETTS, A CORPORATION OF MASSACHUSETTS.

METHOD AND MACHINE FOR MAKING ROOFING ELEMENTS.

Application filed August 26, 1924. Serial No. 734,154.

Prepared roofing is now commonly made by forming a continuous web of fibrous material, such as rag felt, on a paper machine and saturating and coating the web or sheet with asphalt or similar waterproofing material. A surfacing of granular material such as crushed slate is often partially embedded in the coating to provide a fire-proof surface of pleasing color, and which also acts to protect the asphalt from exposure to the weather. After the sheet material is thus prepared it is cut into roofing elements to pack for shipment.

One of the forms in which such material is cut is the so called strip shingle, which comprises a strip having shingle-simulating tabs along one edge defined by narrow slots or cutouts between them. The stock cut out when the slots are formed thus comprises saturated, coated, and surfaced material which is unreclaimable waste. Besides the loss of paper stock, asphalt and surfacing material represented by these cutouts there is also the expense of carting off from the mill and disposing of this rapidly accumulating waste where it will not be objectionable.

According to the present invention the production of this unreclaimable waste is entirely avoided by forming the web of fibrous material with the slots therein as by so forming the cylinder molds that pulp is not deposited thereon over areas corresponding in position and arrangement to the slots in the web before it is cut into strip shingles. The saturant, coating, and surfacing materials thus fail to be deposited over these areas without the necessity of taking any special steps to this end.

For a more complete understanding of this invention reference may be had to the accompanying drawings, in which—

Figure 1 is a somewhat diagrammatic side elevation of a multi-cylinder paper machine designed to function according to this invention.

Figure 2 is a fragmentary elevation of a cylinder mold therefor.

Figure 3 is a cross section on line 3—3 of Figure 2.

Figure 4 is a fragmentary perspective of

a web of sheet material as it comes from the machine.

Figure 5 is a view similar to Figure 4, but showing a modification.

Figures 6, 7 and 8 illustrate various other arrangements and shapes of openings which may be formed by the use of correspondingly shaped unreticulated portions correspondingly positioned on the cylinder mold.

Figures 9, 10 and 11 illustrate forms of roofing to be made from the sheet material formed up according to Figures 6, 7 and 8, respectively.

Referring to Figure 1, 1 indicates the vat of a paper machine in which is partially submerged the cylinder molds 2 in the usual manner. Over the tops of these cylinder molds passes the blanket 3, this blanket picking off from the cylinder molds the pulp deposited thereon and forming a multi-ply sheet in a manner well understood in the art. The blanket as shown passes beneath rollers 5 above each cylinder mold and the multi-ply web formed thereon is removed and passed over the driers (not shown) and the blanket returns in an endless path to again cooperate with the cylinder molds in series in a continuous operation. The cylinder molds are commonly formed of reticulated material so that the water may pass from outside into these molds and drain off therefrom, leaving the pulp deposited on the reticulated surfaces. In order that it may fail to be deposited over the complete areas of the sheet so as to define the cutouts between the shingle simulating tabs, rectangular unreticulated portions corresponding to the areas on which it is not desired to deposit the pulp are formed or fixed to the outer surface of each cylinder mold, this being shown in Figures 2 and 3 at 10, the reticulated surface being indicated at 11.

As shown the portions 10 project somewhat from the periphery of each cylinder mold so as to define sharply the edges of the cutouts, the fibrous material being deposited on the mold over the reticulated portions 11 and failing to be deposited over the substantial areas represented by the portions 10. As shown these portions 10 are ar-

- ranged spaced apart in parallel series corresponding lengthwise of the roll to the widths of the shingle simulating tabs to be formed in the final product, and corresponding circumferentially of the roll to the distance between the tabs where the material is to be cut from the continuous sheet by longitudinal and cross cuts to form strip shingles as shown in Figure 4. At the ends of 5 the cylinder mold imperforate elements 20 each of one-half the width of the imperforate elements 10, but otherwise similar thereto, may be employed to properly form the sides of the sheet material to define notches 10 22 (Figure 4) each of half the width of the slots 12 formed by the elements 10 and in transverse alinement therewith.

It is of course important to rotate the cylinder molds in synchronism so as to cause 20 the slot and notch formations from the successive molds to accurately register on the blanket. This, however, may be readily accomplished by driving the cylinder molds by a common drive shaft 15 by bevel gear 25 connections 16 to each cylinder mold. The shaft 15 is shown as supported in bearings 17 positioned along one side of the vat.

The sheet thus formed with the spaced 30 slots and edge notches is then saturated and otherwise finished, the slots and the notches remaining open and substantially unobstructed throughout the further processes of treating the web. The material having received its final treatment is then cut up 35 into units, which may be done by slitting the sheet lengthwise to define the ends of the strip units, the slit passing centrally through one row of slots, as shown along the line *a—a* in Figure 4, and being chopped off 40 laterally of the sheet through the slots and between the slots as shown on the lines *b—b* and *c—c*, respectively. With this manner of cutting it is evident that the adjacent shingles face oppositely lengthwise 45 of the sheet, the line *c—c* defining the upper edges of adjacent oppositely facing shingles. If it is desired that these shingles shall face in the same direction, this may be done by forming the slots 12 the length of 50 the individual cutouts instead of twice this length as shown in Figure 5, and cutting the sheet crosswise at one end of each series of slots as at *d—d*, there being no intermediate cuts corresponding to *c—c* of Figure 4, and the series of slots being spaced 55 closer together lengthwise of the sheet.

Figure 6 illustrates sheet material formed up with rectangular openings 25 by correspondingly shaped and positioned unreticulated portions on the cylinder mold. By cutting along the dotted lines as at *e—e* and then bending under the lower edges at the ends of the cutouts, as shown in Figure 9, material having a double thick butt slotted 60 through the upper thickness only may be

produced. Such material may be cut to strip shingle length if desired.

Figure 7 shows an arrangement of openings 26 formed in the same manner and which is suitable for strip shingles having 70 semihexagonal tabs, or it may be cut to form individual shingle units 27 of the shape shown in Figure 10.

Figures 8 and 11 are views somewhat similar to Figures 6 and 9, but illustrate 75 longer slots 28 and the material folded substantially midway of the lengths of this slot to form double thick butts slotted through both thicknesses as shown in Figure 11.

Having thus disclosed certain embodiments of this invention it should be understood that various changes and modifications might be made therein without departing from its spirit or scope as defined by the appended claims.

I claim:

1. The method of making roofing which comprises forming a web of fibrous sheet material having spaced openings there-through, saturating the web, and cutting the 90 saturated web into roofing units in a definite relation to said openings.

2. The method of making roofing which comprises forming a web of fibrous sheet material having spaced openings there-through, saturating and coating the web, and cutting the saturated and coated web into 95 roofing units in a definite relation to said openings.

3. The method of making roofing which 100 comprises forming a web of fibrous sheet material having spaced openings there-through, saturating and coating the web, applying a surfacing thereto, and cutting the saturated, coated and surfaced web into 105 roofing units in a definite relation to said openings.

4. The method of making roofing which comprises depositing fibrous material in the 110 form of a felted web having spaced openings therethrough, and cutting the web so formed into roofing units in a definite relation to said openings.

5. The method of making roofing which 115 comprises depositing fibrous material in the form of a felted web having spaced series of parallel slots therein, and cutting said web crosswise and lengthwise of said slots to form roofing units each having shingle 120 simulating tabs separated by said slots.

6. The method of making roofing which 125 comprises depositing fibrous material in the form of a felted web having spaced series of parallel slots therein, treating said web with waterproofing material, and cutting said web crosswise and lengthwise of said slots to form roofing units each having shingle simulating tabs separated by said slots.

7. The method of making roofing which 130 comprises depositing fibrous material in the

form of a felted web having spaced series of parallel slots therein, treating said web with waterproofing material, applying a surfacing to said treated web, and cutting said web crosswise and lengthwise of said slots to form roofing units each having shingle simulating tabs separated by said slots.

8. The method of making roofing which comprises depositing fibrous material in the

form of a felted web having spaced openings ¹⁰ therethrough, treating said web with waterproofing material, and cutting said treated web into roofing units in definite relation to said openings.

In testimony whereof I have affixed my ¹⁵ signature.

CHESTER E. RAHR.
